US00D517713S

(12) **United States Design Patent** (10) Patent No.: **US D517,713 S**
Waldmann (45) Date of Patent: **** Mar. 21, 2006**

(54) **LAMP**

(75) Inventor: **Gerhard Waldmann**, Dauchingen (DE)

(73) Assignee: **Herbert Waldmann GmbH & Co.**
(DE)

(**) Term: **14 Years**

(21) Appl. No.: **29/179,384**

(22) Filed: **Apr. 9, 2003**

(30) **Foreign Application Priority Data**

Oct. 10, 2002 (DE) 4 02 08 397

(51) LOC (8) Cl. **26-05**

(52) U.S. Cl. **D26/60; D26/65**

(58) **Field of Classification Search** D26/60-66,
D26/93, 102-112; 362/267, 269, 271, 272,
362/273, 276, 282, 283, 285, 287, 410-414,
362/418, 419, 427

See application file for complete search history.

(57) **CLAIM**

The ornamental design for lamp, as shown and described.

DESCRIPTION

FIG. 1 is a perspective view of my new design for a lamp; FIG. 2 is a side elevational view of my new design for a lamp;

FIG. 3 is a front elevational view of my new design for a lamp;

FIG. 4 is a side elevational view of my new design for a lamp showing the side opposite that shown in FIG. 2;

FIG. 5 is a rear elevational view of my new design for a lamp;

FIG. 6 is a top plan view of my new design for a lamp; and, FIG. 7 is a bottom plan view of my new design for a lamp.

UNITED STATES PATENT AND TRADEMARK OFFICE
CERTIFICATE OF CORRECTION

PATENT NO. : Des. 517,713 S
APPLICATION NO. : 29/179384
DATED : March 21, 2006
INVENTOR(S) : Gerhard Waldmann

Page 1 of 9

It is certified that error appears in the above-identified patent and that said Letters Patent is hereby corrected as shown below:

The Title Page, showing an illustrative figure, should be deleted and substitute therefor the attached Title Page.

Delete drawings sheets 1-7 and substitute therefor the drawing sheets, consisting of figs. 1-7 as shown on the attached page.

Signed and Sealed this

Eighth Day of January, 2008

JON W. DUDAS
Director of the United States Patent and Trademark Office
